CLAIM

The ornamental design for a transport container for animals, as shown and described.

DESCRIPTION

1.-2. Transport containers for animals

Fig.1.1 is a first design model showing an isometric view of a container for animals; fig.1.2 is a different view of the container of fig.1.1; fig.1.3 is a lateral view of the container of fig.1.1; fig.1.4 is a front view of the container of fig.1.1; fig.1.5 is a rear view of the container of fig.1.1; fig.1.6 is a plan view of the container of fig.1.1; fig.1.7 is a below view of the container of fig.1.1; fig.2.1 is a second design model showing an isometric view of a container for animals; fig.2.2 is a different view of the container of fig.2.1; fig.2.3 is a lateral view of the container of fig.2.1; fig.2.4 is a front view of the container of fig.2.1; fig.2.5 is a rear view of the container of fig.2.1; fig.2.6 is a plan view of the container of fig.2.1; fig.2.7 is a below view of the container of fig.2.1. The broken lines depict environmental subject matter and form no part of the claimed design.
